UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

PUMPING SYSTEM.

Application filed July 28, 1919. Serial No. 313,852.

To all whom it may concern:

Be it known that I, FRED D. HOLDSWORTH, a citizen of the United States, residing at Claremont, in the county of Sullivan and State of New Hampshire, have invented certain new and useful Improvements in Pumping Systems, of which the following is a full, clear, and exact specification.

My invention relates to pumping systems.

10 It has for its object to provide an improved and simplified pumping system and one especially adapted to use under those conditions wherein a plurality of operating pressures is required. A further object of 15 my invention is to provide an improved and simplified pumping system especially adapted to use in connection with well pumping and more especially to oil well pumping wherein a high initial or starting 20 pressure is required to blow off the head above the pump and a low running pressure is sufficient to maintain the supply after the flow from the well has been started. These 25 and other objects and advantages of my improved construction will, however, herein-after more fully appear.

For purposes of illustration I have shown in the accompanying drawings two forms which my invention may assume in practice, 30 illustrating the same herein as applied to use in connection with an air lift system adapted to well pumping.

In these drawings,—

35 Fig. 1 is a side elevation partially in section showing a pumping system embodying one form of my invention.

Fig. 2 is a detailed view partially in section showing a modified construction adapted to be incorporated in said system.

40 In this illustrative construction I have shown an air lift system including a multi-stage compressor 1, having a low pressure cylinder 2 discharging into an intercooler 3 which in turn communicates with a high pressure cylinder 4 delivering to a receiver 5, the receiver in turn communicating through piping herein controlled by a check valve 6 with a down pipe 7 of an air lift pump 8 disposed within the well casing 9 and discharging into a discharge line 10.

45 In my improved construction, it will be observed that I have provided improved operating compressing means operatively connected to and driven by the compressor 50 unit 1, which means serve further to compress

the pressure fluid compressed thereby and are adapted to be rendered operative or inoperative at will without interfering with the operation of the unit 1. While these means may assume various forms, in the 55 form of my invention shown in Fig. 1 it will be observed that I have connected a supplemental piston 11 coaxially with the piston of the low pressure cylinder 2 and that I have connected a supplemental cylinder 12, herein a double acting single stage cylinder, coaxially with the low pressure cylinder 2, the supplemental cylinder being provided with usual intake valves 13 preferably of the suction type controlling the 60 supply of air supplied from the receiver to the cylinder 12 through a pipe 14, and usual discharge valves 15 discharging into a discharge pipe 16 controlled by a throttle valve 17, and connected to the down pipe 7 of the pump. A valve 17' is likewise provided in the pipe line 14. Also it will be observed that I have provided controlling means herein in a form adapted to render 65 this supplemental cylinder ineffective by unloading the same, and comprising adjustable controlling members 18, threaded in the cylinder casing, as shown in Fig. 2, and adapted to engage the outer ends of the 70 spring pressed valve members 19 of the inlet 75 valves 13 and thereby raise the latter from their seats 20 in such a manner as to unload 80 the cylinder.

In Fig. 2 I have illustrated a modified construction which may be embodied in the 85 supplemental cylinder if desired. In this construction it will be observed that inlet and discharge valves are provided at each 90 end of the cylinder as heretofore and that a web 21 is provided substantially midway 95 between the ends of the inlet and discharge 100 openings in such a manner as to convert the cylinder into a single acting two-stage cylinder, this being accomplished by so proportioning the piston rod that the 105 volumes at opposite sides of the piston will be in correct ratio for multi-stage operation. Here it will be noted that I have also provided a supplemental connection 22 leading 110 from the discharge chamber of the low pressure discharge, herein indicated at 23, to the high pressure inlet chamber, herein indicated at 24. By this construction it will be observed that the air compressed by the unit 1 through a plurality of stages and re-

ceived by the supplemental cylinder, is compressed by the latter through two additional stages in such a manner as even further to increase its pressure before it is delivered to the discharge pipe 16 leading to the pump.

5 In the operation of my improved system, it will be observed that the air is compressed through a plurality of stages by the compressor unit 1 and delivered thereby to the receiver 5 which is in turn connected to the down pipe 7 of the pump 8 and to the pipe 14 leading to the intake of the supplemental cylinder, the latter also being connected to the down pipe 7. As a result, when the controlling members 18 are lowered out of engagement with the suction valve members 19 of the supplemental cylinder and the valve 17 is open, the fluid compressed through two stages by the unit 1 will be 10 further compressed in the supplemental cylinder either through an additional stage or two additional stages depending upon whether the construction shown in Fig. 1 or that shown in Fig. 2 is used, and delivered 15 from the supplemental cylinder at a very high pressure to the down pipe of the pump through which it acts to blow off the head accumulated in the head above the pump, i. e. to start the well. When the well is thus 20 started it will also be observed that by simply advancing the controlling members 18 in such a manner as thereby to elevate the suction inlet valve members 19, and thereafter preferably also closing the valves in 25 the connections leading to and from that cylinder, the latter will be unloaded and thereafter cut out of the circuit without in any way interfering with the continued operation of the unit 1, which continues to supply 30 the low pressure sufficient to maintain the well flow.

As a result of my improved construction, it will be observed that it is possible materially to decrease the cost of a pumping 45 installation of the character set forth, it only being necessary to connect to a compressor of standard construction a supplemental cylinder and to connect this cylinder by suitable piping to the receiver and the down pipe of the pump. It will also be noted that this supplemental cylinder during operation in no way interferes with the operation of the primary pumping unit and that as soon as this cylinder is unloaded, 50 that unit is enabled to operate without appreciable additional load during the normal pumping operation. It will also be observed that whenever desired the supplemental cylinder and its connected parts may be removed from the primary unit, thereby enabling the latter to be used in other relations when desired.

While I have in this application specifically described two forms which my invention 55 may assume in practice, it will be understood

that these forms of the same are shown for purposes of illustration and that the invention may be modified and embodied in other forms without departing from its spirit or the scope of the appended claims.

What I claim as new and desire to secure by Letters Patent is:

1. In an air lift pumping system, means adapted to discharge an excess and normal head including a down pipe and supply means connected thereto, said latter means comprising a compressor mechanism, a co-operating compressor mechanism driven thereby and connected in multi-stage relation therewith, and means for rendering said last mentioned mechanism ineffective while continuing the operation of the other.

2. In an air lift pumping system, means adapted to discharge an excess and normal head including a down pipe and supply means connected thereto, said latter means comprising a compressor mechanism, a co-operating compressor mechanism driven thereby and connected in multi-stage relation therewith, and means for unloading the latter mechanism while continuing the operation of the former.

3. In an air lift pumping system, means adapted to discharge first an excess and then a normal head including a down pipe and supply means connected thereto, said latter means comprising a compressor mechanism including a cylinder and a reciprocating piston, a co-operating compressor mechanism including a cylinder and a piston driven by said piston, and means for unloading said last mentioned cylinder while continuing the operation of both of said pistons.

4. In an air lift pumping system, means adapted to discharge an excess and normal head including a down pipe and supply means connected thereto, said latter means comprising a multi-stage compressor, a receiver receiving the discharge therefrom, a co-operating multi-stage compressor driven by said compressor and having its intake supplied from said receiver, and means for unloading said co-operating compressor when desired.

5. In a pumping system, means adapted to discharge an excess and normal head including a multi-stage compressor, a receiver connected thereto, a co-operating compressor driven by said compressor and connected to said receiver, an air lift pump connected to said receiver and last mentioned compressor to pump an excess head, and means for unloading said last mentioned compressor when desired to pump a normal head after said excess head is pumped.

6. In a pumping system, means for discharging an excess and normal head from a single level including a multi-stage compressor mechanism, a multi-stage cylinder

connected thereto and having a piston therein driven by said mechanism, a receiver connected between said first mentioned compressor and the inlet of said cylinder, an air lift pump connected to said cylinder and to said receiver, and means for unloading said cylinder when desired.

7. In a pumping system having an air lift pump adapted to discharge an excess 10 and normal head from a single level, means for actuating said pump comprising compressor mechanism including a cylinder and a piston therein, cooperating compressor mechanism including a coaxially disposed 15 cylinder and a piston therein movable with said first mentioned piston, valve mechanism in said last mentioned cylinder, and means co-operating with said valve mechanism for unloading said last mentioned cylinder while 20 continuing compression in said first mentioned cylinder.

8. In a compressor mechanism, a compressor including a cylinder and a movable piston, a receiver connected to said cylinder, a 25 cooperating compressor mechanism including a cylinder and a piston in the latter movable with said first mentioned piston, and inlet valves controlling the supply to said cylinder from said receiver, an air lift 30 pump connected to said receiver and to said last mentioned cylinder, said pump being adapted to discharge from a single level both an excess and normal head, and means for operating said valves to unload said 35 cylinder.

9. In an air lift pumping system, an air lift pump having a down pipe, and means for supplying pumping fluid to said down pipe at different pressures comprising a 40 compressor, a receiver connected to the discharge side thereof, a valved connection between said receiver and said down pipe, a second compressor driven by said first compressor and having its intake connected to said receiver and also having a valved connection to said down pipe, and means co-operating with the inlet valves of said last 45 mentioned compressor to unload the latter at will.

50 10. In an air lift pumping system, an air lift pump having a down pipe terminating in a foot piece which discharges at a single level, means for supplying pumping fluid to said foot piece at a pressure sufficient to 55 maintain the pump in operation when normally running, comprising a compressor whose discharge is connected to said down pipe, and means for raising the pressure of the pumping fluid supply for said down 60 pipe sufficiently to enable discharge of a head whose static pressure is in excess of the discharge pressure of said compressor comprising a second compressor driven from said first mentioned compressor.

65 11. In an air lift pumping system, an air

lift pump having a down pipe terminating in a foot piece, means for supplying pumping fluid to said foot piece at a pressure sufficient to maintain the pump in operation when normally running comprising a compressor, a receiver to which said compressor discharges, and a connection between the latter and the down pipe provided with a check valve opening towards the down pipe, the initial submergence of said foot piece 70 being such that the static head to be overcome is in excess of the designed discharge pressure of said compressor, and means for raising the pressure of the pumping fluid supply for said down pipe sufficiently to enable discharge of the excess head comprising a second compressor driven from said first mentioned compressor and discharging to the line connecting the receiver and down pipe at a point in the latter between the 75 check valve and the foot piece.

12. In an air lift pumping system having a pressure fluid discharge means positioned at a single level, means adapted to discharge only a normal head in said system, and a 80 second means actuated by and cooperating with said latter means for discharging an excessive head before normal operation of said system.

13. In an air lift pumping system having pumping means adapted to discharge at substantially a single level, a plurality of means adapted to discharge a normal and excess head, and means for effecting the operation of one of said latter means by the other 95 thereof.

14. In an air lift pumping system having pumping means for discharging an excess and normal head, a plurality of means adapted to discharge said heads, and means including mechanically connected means for effecting the operation of one of said latter means by the other thereof.

15. In an air lift system, the combination including a pump adapted to discharge from a single level, and means for effecting operation of said pump including compressor mechanism comprising low pressure compressing means having a receiver and a discharge line connected to said receiver, high pressure compressing means driven by said first mentioned means having a separate discharge line and its inlet connected to said receiver, the fluid under low pressure being discharged through a single conduit, and means whereby during discharge of fluid under low pressure, fluid flow under high pressure is discontinued.

16. In an air lift system, the combination including a pump adapted to discharge from a single level, and means for effecting operation of said pump including compressor mechanism comprising a low pressure compressing means having a receiver and a discharge line connected to said receiver, high 120 pressure compressing means driven by said 125 first mentioned means having a separate discharge line and its inlet connected to said receiver, the fluid under low pressure being discharged through a single conduit, and means whereby during discharge of fluid under low pressure, fluid flow under high pressure is discontinued.

- pressure compressing means driven by said first mentioned means having its inlet connected to said receiver and a separate discharge line connected to said first mentioned discharge line, and the fluid flow under low pressure being discharged through a single conduit, and means whereby during discharge of fluid under low pressure, fluid flow under high pressure is discontinued.
17. An air lift pumping system having pumping means adapted to discharge an excess and normal head including a plurality of mechanically connected compressor elements one being operative to pump the excess head and the other the normal head.
18. In an air lift pumping system having pumping means adapted to discharge an excess and normal head from a single level, a

plurality of means for effecting the air supply and adapted to allow discharge of a normal and excess head, and means whereby the actuation of one of said means is dependent upon the other thereof.

19. In an air lift pumping system having pumping means adapted to discharge at substantially a single level, a unitary compressor mechanism adapted to generate varying degrees of pressure of the air supply, the latter at certain pressures being adapted to discharge an excess head, while the air at other pressures is adapted to discharge a normal head but insufficient to discharge the excess head.

In testimony whereof I affix my signature.

FRED D. HOLDSWORTH.
